UNITED STATES PATENT OFFICE.

EDMUND SCHROEDTER, OF BROOKLYN, NEW YORK, ASSIGNOR TO THE O. MAURER COMPANY, INCORPORATED, OF BROOKLYN, NEW YORK, A CORPORATION OF NEW YORK.

ASH-RECEIVER.

1,401,282.

Specification of Letters Patent. Patented Dec. 27, 1921.

Application filed June 29, 1920. Serial No. 392,628.

To all whom it may concern:

Be it known that I, EDMUND SCHROEDTER, a citizen of the United States, and a resident of Brooklyn, Kings county, and State of New York, have invented certain new and useful Improvements in Ash-Receiver, of which the following is a specification.

My present invention is a receiver for cigar and cigarette ashes particularly designed for use in sedans and in other closed cars.

The objects of the invention are to provide a holder which will be ready at all times to receive the ashes, which will prevent scattering of the ashes and which can be quickly and easily emptied and cleaned.

The invention involves a number of novel features of construction, combinations and relations of parts, as will be disclosed in the following specification, which is to be read in conjunction with the drawing accompanying and forming a part thereof.

In the drawing referred to:

Figure 1 is a perspective view showing the cover as lifted off of the receptacle.

Fig. 2 is a vertical sectional view of the complete device.

Fig. 3 is a detached detail view of the hinged flap.

The body of the device consists of a receptacle 5 of convenient size and shape, the same being herein shown as of substantially semi-cylindrical form in cross section, and as having a back wall 6 adapted to rest flat against the supporting structure, such as the dash of the automobile. This back wall is also shown as provided with means by which the device is detachably mounted on its support, such means including the key hole slots 7 to receive headed supporting studs projecting from the face of the supporting structure.

The upper end of the receptacle is preferably cut on an outward and downward slant, as indicated in Fig. 1. This upper end of the receptacle originally is entirely open, but in the completed device is closed by an inclined cover 8 which is shown pivoted at its upper edge at 9 to the rear or back wall of the receptacle. This cover may be formed with a dependent flange 10 fitting closely over the mouth of the holder, but so arranged as to not interfere with the cover swinging freely open when the receptacle is

detached from its support and reversed to empty the contents.

In the central portion of the cover there is provided an ash receiving opening 11 and about this opening there is provided an ash confining guard flange 12. The upper edge 60 of this flange may be substantially horizontal, as shown, so as to form both a guard and a pocket receiving the ash-end of the cigar or cigarette and directing the ashes into the opening.

The ash opening is closed by a flap or door 13 hinged at 14 to the under side of the cover and suitably counterweighted as indicated at 15 so as to automatically swing closed as soon as pressure on the same is released.

In use, the cigar or cigarette is merely touched against this flap, which swings freely open and drops the ashes into the receptacle, closing again as soon as the opening force is removed. The guard flange about the opening both guides the cigar or cigarette and confines any stray ashes which may be flicked off, causing the same to drop through the opening as the flap swings inward. When the receptacle is to be emptied, it is simply removed from its support by lifting it far enough to enable the heads of the supporting studs to pass through the enlargements in the key hole slots and then, 85 upon inverting the receptacle, the cover will swing open and empty the entire contents.

The downwardly inclined upper edge of the receptacle gives full access to the interior of the receptacle, and this, with the wide 90 open swinging of the cover and the easy removability of the receptacle from its support, facilitates and promotes the cleaning of the receiver so that the same may be easily kept in a sanitary and wholesome condition.

In the particular construction herein shown the cover is hinged by means of a pin inserted through pivot openings 16 provided in the dependent flange 10 of the cover and 100 through openings 17 in the side walls of the receptacle, said pin being headed over or otherwise fixed in this relation. Also in this particular illustration the cover is provided at the rear with a dependent flange 18, the 10 back of the receptacle being cut down at 19 to receive the same. This dependent flange, when the receptacle is engaged with its sup-

port, may bear against the surface of the support so as to prevent the cover being lifted when the device is attached to its support. This prevents the cover from rattling 5 and from being lifted accidentally or otherwise, so long as the device is attached to its support, but when the receiver is removed from the support, the rearward flange 18 of the cover no longer prevents the cover 10 from swinging freely open and therefore does not interfere in any way with the emptying of the contents.

The downward slant of the cover also, it will be clear, prevents the wind from blowing 15 the ashes out of the receiver when the trap door is opened.

What I claim is:

1. An ash receiver comprising a receptacle provided with means by which the same may 20 be removably mounted on a supporting structure and having a cover adapted to be held in closed position by said supporting structure, said receptacle having an ash receiving

passage, a closure for said passage, and means for holding said closure normally closed but 25 sensitive to the opening pressure of the ash end of a lighted cigar or cigarette.

2. An ash receiver comprising a receptacle provided with an ash passage and with a closure therefor opening into the receptacle 30 and balanced to normally stand closed but to open upon contact of the lighted end of a cigar or cigarette therewith and an upstanding external guiding and ash confining flange about the ash passage.

3. An ash receptacle having an ash passage and a downwardly inclined closure therefor pivotally supported at its upper end and lightly balanced to normally stand closed but 40 sensitive to open upon contact of the ash end of a cigar or cigarette therewith.

In witness whereof I have hereunto set my hand this 19th day of June, 1920.

EDMUND SCHROEDTER.
